Elias T. Ford

United States Patent Office.

ELIAS T. FORD, OF STILLWATER, NEW YORK.

Letters Patent No. 83,618, dated November 3, 1868.

IMPROVEMENT IN WRENCH.

The Schedule referred to in these Letters Patent and making part of the same.

To all whom it may concern:

Be it known that I, ELIAS T. FORD, of the town of Stillwater, in the county of Saratoga, and State of New York, have invented a new and useful Improvement in a Carriage-Wrench, used for handling the axle-nuts upon carriages, with the wheels; and I do hereby declare that the following is an exact and full description thereof, reference being had to the accompanying drawings, and to the letters of reference marked thereon.

The nature of my invention consists in the construction and attachment of a wrench to the axle-nuts and wheels of carriages, said wrench having adjustable fixtures, possessing the functions of fastening to the nut, upon the extremity of the axle, in connection with the wheel A, which is also coupled with the nut, and using the wheel as the lever, in turning the nut on or off the axle, without greasing the hands of the operator in the act of lubricating the carriage-axle; and to enable others skilled in the art to make and use my invention, I will proceed to describe its construction and operation.

Figure 1 represents the wrench, attached both to the axle-nut and wagon-wheel.

The wrench is seen as a whole in Figure 2 and Figure 3.

Figure 4 and Figure 5 are detached sections of fig. 2, with the exception of the flange e.

Construction.

As seen in fig. 2, I take out the guide-bolt or screw a from the right jaw E, as seen in fig. 5, and locate the jaw E underneath the section C, seen in fig. 4, and retain the same by means of the bolt a, a thread being cut upon this lower extremity.

I now insert the spoke-holder, section D, upon the front portion of section C r, it having an aperture and set-screw, H, as seen in fig. 2.

The holder D is adjustable upon the section C r, or the section D may be adjusted with a longer screw, H I, as seen in fig. 3, the section C having the projection e attached, and the adjustable screw H I passing

through it, also through the rear portion of section D, entering between the two parts C and D, if necessary; or the left extremity of the screw H I may be connected to the rear portion of section D, in a manner similar to the construction of the adjustable screw F, as seen in fig. 2 and fig. 5.

The front portion of the screw F is made smaller, so as to form a shoulder next to the thread cut thereon, and it passes through the jaw E. The front extremity is riveted, so that it cannot draw out, but turns within its orifice, as seen in fig. 5.

Operation.

The wrench, as seen in fig. 2, is now placed upon the nut of the axle, as seen in fig. 1. The section D, with the arm C r, extends back between the spokes of the wheel A, and the curve n embraces one spoke. The parts C and D are pressed snugly together, and are held by the set-screw H, or by the longer screw H I, as seen in fig. 3. The right jaw E, as seen in fig. 2, is adjustable, and is moved right and left by means of the screw F.

The right and left jaws of the wrench are contracted or operated by the screw F, the wrench being retained in its position by the hook D clasping a spoke of the wheel A. The wheel A is now easily turned, running the axle-nut on or off, for the purpose of lubricating the axle or axles of carriages or wagons, using the circumference of the wheel A for the lever, and not being under the necessity of handling the nut and blackening the hands, as before stated.

What I claim, and desire to secure by Letters Patent, is—

The above-described wrench for axle-nuts of carriages, the whole constructed and operated substantially as and for the purpose specified.

ELIAS T. FORD.
